UNITED STATES PATENT OFFICE

2,570,068

KEYBOARD INTERLOCK FOR CALCULATING MACHINES

Frederick A. Niemann, Chicago, Ill., assignor to
Felt & Tarrant Manufacturing Company, Chicago, Ill., a corporation of Illinois

Application June 15, 1945, Serial No. 599,561

14 Claims. (Cl. 235—130)

1

This invention relates in general to calculating machines, and more particularly to error preventing mechanism for key-driven calculating machines, such as the well-known duplex "Comptometer."

Such key-driven calculating machines are especially well adapted for rapid operation in all types of calculation; maximum speed being attained by a trained operator in addition and subtraction by employing only the first five ordinal keys ("1"—"5") in the various denominations, and in multiplication and division by actuating a key in each desired denominational order simultaneously using a different finger for each order and both hands if necessary.

Error control mechanism has been provided in the prior art for preventing mismanipulation due to partial key strokes, such as that disclosed in United States Letters Patent No. 1,818,425 granted August 11, 1931, to Frederick A. Niemann, which retains a partially depressed key in a partially depressed position and locks all other keys of the machine against actuation, while permitting correction of the error by complete depression of the partially operated key, which also is then locked against actuation upon its return to normal position. The mechanism provided by the prior art, however, has certain disadvantages; for example, a plurality of keys in any one denominational order can be partially depressed; if only one is corrected, the others partially depressed also are restored to elevated position but without correction. Another disadvantage of the prior art mechanism is that regardless of the extent of partial depression of any ordinal key, that key is retained only in a very slightly partially depressed position, thereby offering a relatively poor visual indication of which key was partially depressed and requires corrective actuation.

A principal object of the instant invention is the provision in a calculating machine of improved error preventing mechanism operable differently during different types of calculation to obviate and prevent mismanipulation due to partial depression of ordinal keys in the manner best suited to the particular method of machine calculations being employed.

Another important object of the invention is the provision of novel means for releasably latching any ordinal key to its associated actuating mechanism throughout the active phase of a complete operation of said key.

Another important object of the invention is the provision of means for retaining any ordinal

2

key or keys which have been partially depressed, in such partially depressed position, substantially equal in depressive extent to the degree of partial actuation imparted thereto, so as to offer a distinct and instantly recognizable visual indication of which key or keys require corrective actuation.

A further important object is the provision of such mechanism which also prevents depression of more than one key at a time in each denominational order and locks the entire keyboard against actuation upon partial depression of any ordinal key or keys, except the key or keys partially depressed, which are retained in that position.

15 Another object of the invention is to provide means particularly useful during the performance of addition or subtraction to effect locking of any partially depressed key upon its return to normal position following corrective complete depression thereof, and control mechanism manually operable to release for actuation the entire keyboard thus locked.

20 A further important object of the invention is the provision of an error correction control, particularly useful during the performance of multiplication or division, which is selectively operable to render ineffective the above referred to means for locking partially depressed keys following corrective actuation thereof, whereby complete depression of all keys partially depressed causes immediate automatic unlocking of the entire keyboard.

25 Another object is to provide error correction means for positively assuring that complete corrective depression is imparted to all partially depressed ordinal keys.

30 A further object of the invention is the provision of yieldable means associated with the means for retaining ordinal keys in partially depressed positions which will prevent injuring the mechanism by any attempts to force partially depressed keys upwardly.

35 Numerous other objects and advantages of the invention will be apparent as it is better understood from the following description which, when taken in connection with the accompanying drawings, discloses a preferred embodiment thereof.

40 In the drawings:

Fig. 1 is a plan view of a calculating machine of the multiple order, key-driven type in which the present invention is embodied;

45 Fig. 2 is a side elevational view of the front portion of the machine, as seen from the left of

Fig. 1, with part of the side wall of the casing removed;

Fig. 3 is a side elevation, viewed from the left of Fig. 1, with part of the casing removed and the front portion of the machine and some other mechanism omitted, showing the mechanism associated with one denominational order in normal or inoperative position;

Fig. 4 is a view similar to Fig. 3 showing one of the digital keys (the "8" key) at that point of initial depression just prior to forward movement being imparted thereby to the associated auxiliary key lock lever;

Fig. 5 is a view similar to Figs. 3 and 4 showing a digital key in a partially depressed position;

Fig. 6 is a view similar to Figs. 3 to 5, showing a digital key, which has been partially depressed and released, locked in partially depressed position;

Fig. 7 is a view similar to Figs. 3 to 6, with the additional disclosure of the ordinal gang key locking mechanism, and showing the previously illustrated, partially depressed, digital key in fully depressed position;

Fig. 8 is a detail view of part of the ordinal mechanism showing the position assumed thereby during return movement of a digital key which has been fully depressed;

Fig. 9 is an enlarged detail view similar to Fig. 3;

Fig. 10 is an enlarged detail view similar to Fig. 5;

Fig. 11 is an enlarged detail view similar to Fig. 6;

Fig. 12 is an enlarged detail view similar to Fig. 7;

Fig. 13 is an enlarged detail plan view, similar to Fig. 1, of part of the left-hand portion of the machine, with some of the casing removed and part of the mechanism of the highest denominational order in horizontal section;

Fig. 14 is a detail perspective of part of the mechanism of Fig. 8;

Fig. 15 is a detail perspective of an ordinal key lock lever actuator;

Figs. 16 and 17 are detail vertical cross sections on lines 16-16 and 17-17, respectively, of Fig. 3;

Fig. 18 is a detail side elevation, similar to Fig. 3, showing the error correction mechanism in active position;

Fig. 19 is a view similar to Fig. 18 of part of the error correction mechanism in active, actuated position;

Fig. 20 is a detail view similar to Fig. 18 of the error correction key mechanism in inactive position; and

Figs. 21, 22 and 23 are detail perspective views of some of the latch levers of the error control mechanism.

The general construction of the "Comptometer" herein illustrated is described in the following Letters Patent of the United States: Dorr E. Felt, No. 762,520 and No. 762,521, granted June 29, 1904; No. 1,028,344, granted June 4, 1912; No. 1,066,096, granted July 1, 1913; No. 1,072,933, granted September 9, 1913; Kurt F. Ziehm, No. 1,110,734, granted September 15, 1941; Joseph A. V. Turck, No. 1,357,747 and No. 1,357,748, granted November 2, 1920, and No. 1,449,639, granted March 27, 1923, and Frederick A. Niemann, No. 1,818,425, granted August 11, 1931.

Since the details of construction and operation of the instant calculating machine are described in the above-listed Letters Patent of the

United States, a brief description of the general features of this machine will be sufficient for an understanding of this invention.

The various parts and mechanisms of the illustrative machine are supported by skeleton framework mounted on the base plate of a casing 21. This framework includes side skeleton plates 22 (Figs. 2 and 13) and intermediate skeleton plates 23 located respectively at the right and left sides of the machine and between the several orders thereof. These plates 22 and 23 are tied together by a number of transverse tie rods 24 (Figs. 2, 7, and 13), providing a rigid construction on which are mounted the movable parts 15 of the machine.

A number of duplicate orders each having nine (9) digital keys 25 is provided, and each order or column of keys is coordinated with a registering or numeral wheel, by means of interposed 20 actuating and accumulator mechanisms and other parts. The keys 25 of each order are adapted to induce the operation of the corresponding actuating mechanism which transmits to an accumulator mechanism, including the registering wheels, and amount of travel determined by and proportioned to the numerical value of the particular key operated.

The actuating mechanism of each order includes a column actuator 26, in the form of a 30 segment lever pivoted at the rear end of the machine and adapted to be depressed varying distances, determined by any particular key 25 of that order struck by the operator. The keys are provided with stems 27 which extend down 35 and bear upon the corresponding column actuator 26, for the purpose of transmitting thereto movement induced by depressing the keys.

The key at the extreme front of the machine, being further from the axis of the column actuator than the key at the extreme rear of the machine, moves the column actuator a shorter distance than does the rear key last mentioned. The keys of each column are numbered from 40 "1" to "9" from the front to the rear of the machine. The "1" key at the extreme front moves the column actuator a distance substantially one-ninth of that effected by the operation of the "9" key at the extreme rear of the machine. Upon depression of intermediately positioned keys, the column actuator is operated distances respectively proportioned to the value of the intermediate key operated.

Each column actuator 26, when operated, imparts calculating movement to its corresponding accumulator mechanism, and, for this purpose, is provided at its forward end with a rack 28 (Fig. 2) which meshes with an accumulator pinion 29 journaled on a transverse shaft 30 extending across the machine and supported in the framework. The pinion 29 of each order is coordinated with an internal ratchet mechanism, not herein described, but fully set forth in certain of the United States patents hereinbefore mentioned (see particularly Patents Nos. 762,520, 762,521, 1,028,344, 1,066,096, 1,072,933, and 1,110,734).

It will be sufficient to state that the ratchet mechanism is interposed between the pinion 29 and the lantern wheel 31 and becomes effective on the up-stroke of the column actuator to clutch the pinion 29 to the lantern wheel 31, which normally is connected operatively by a gear train 33 (Fig. 2) with the numeral wheel pinion 36. The numeral wheel pinion 36 is journaled on the transverse shaft 37 and is secured

to its corresponding numeral or registering wheel 38. During the downward movement of a column actuator 26, the internal ratchet mechanism moves idly with respect to the lantern wheel 31, so that the gear train 33 and the numeral wheel pinion 36 remain stationary. However, during the return or up-stroke of the column actuator, the clutching of the accumulator pinion 29 to the lantern wheel 31, by said internal ratchet mechanism, operates the interposed gear train 10 33, so that the numeral wheel 38 is rotated a distance determined by the particular key of its corresponding order that has been first depressed and next released. Whenever an actuated key is released at the end of a full downward stroke, the column actuator is moved upwardly by the column actuator springs 39 (Figs. 3 and 13).

Carrying mechanism is cooperatively combined with each ordinal accumulator mechanism for the purpose of actuating the accumulator mechanism of the next higher order of the machine whenever a carry is to go over from a lower order. This carrying mechanism is illustrated in detail in Patents No. 1,357,747 and No. 1,357,748, and described in a general manner in Patent No. 1,818,425.

Those patents also specifically illustrate and describe zeroizing or canceling mechanism for returning the register wheels and other parts to normal or inoperative position.

Means are provided for relieving the digital keys of the necessity of stopping the respectively associated column actuators in their downward movement and for insuring accurate extent of movement thereof comprising in each order of the machine even and odd key stop levers 50 and 51, best illustrated in Figs. 7 and 17, which are mounted for pivotal movement at the rear of the machine upon a transverse rod 52. One of each of such key stop levers 50 and 51 is associated with each column or order of the digital keys 25. In the final portion of the downward movement of any of the digital keys 25, a laterally extending shoulder 53 on the stem 27 thereof imparts a slight degree of downward movement to its associated key stop lever 50 or 51, depending upon whether such key is of even or odd digital value. This downward pivotal movement of the key stop lever swings an associated even or odd actuator stop lever 54 or 55 in a counter-clockwise direction, viewed in Figs. 7 and 12, to carry a suitable stop lug 56 (Fig. 7) on the depending end thereof forwardly into engagement with the proper one of a series of teeth 57 provided on the rear edge of the rack end 28 of the column actuator 26. The specific construction and detailed operation of this particular stop mechanism is fully illustrated and described in Patent No. 762,520.

Means are provided for, among other functions, preventing actuation of the accumulator during downward pivotal movement of the column actuator 26. In each denominational order of the machine an auxiliary key lock lever 86, provided at its rear end with an elongated aperture 84, is by means of that aperture pivotally and reciprocably mounted on a cross rod 85 which is suitably supported at the rear of the machine and which forms the pivot for all of the column actuators 26. Each auxiliary key lock lever 86 is provided with upstanding shoulders or projections 87 adapted, upon initial depression of any one of the associated digital keys 25, to be con-

tacted by a lateral projection 58 (Fig. 17) formed on each of the key stems 27. The lever 86 is further provided with a roller 88 which rests on the horizontal forwardly extending arm 89 of an elbow lever 90 pivoted at 91 on the column actuator 26. The elbow lever has an inner vertical arm 92 (Fig. 13) which is connected by a spring 93 to the associated column actuator 26, so that the elbow lever is normally pulled back into vertical position with its horizontal arm bearing up against the roller 88 of the key lock lever 86. The elbow lever 90 also has an outer vertical arm 94 pivotally connected with a forwardly extending link 95. This pivotal connection is of the pin and slot type which permits a slight forward and rearward relative movement between the arm 94 and the link 95, the latter normally being retained in its forwardmost position of Fig. 3 by a spring 96 extending between the uppermost ends of these two parts.

Each link 95 is connected by a pivot 97 at its forward end to a swinging link 98 pivotally mounted in the frame of the machine at 99 and having a forwardly extending arm 100 adapted to limit counterclockwise movement thereof, as viewed from the left of the machine, by contact with a cross rod 101.

The pivot 97 carries in each denominational order a forwardly and backwardly and upwardly and downwardly movable lever 103, the forward arm of which is urged upwardly by a spring 105 connected at its upper end to the cross rod 101. The forward end of each lever 103 is provided 35 with a pin 106 which engages a slotted arm 107 of an accumulator locking detent lever 108, there being one such lever 108 pivoted in each denominational order on a cross rod 109. With this arrangement, the forward arm of the lever 103 and the arm 107 of the detent lever, during upward and downward movement thereof, will respectively engage and disengage the forward depending end of the detent with and from the lantern wheel 31 of the associated accumulator mechanism. When the said detent engages the said lantern wheel, it and its accumulator mechanism are locked against rotation, and it is necessary to remove the detent when and as the downward movement of the column actuator 26 is completed to permit the actuator to impart movement to the accumulator during its return stroke.

The major portion of this mechanism is disclosed in greater detail in Patent No. 1,110,734. In the final portion of the downward movement of any of the digital keys 25, the resulting actuation of the associated key stop lever 50 or 51 and actuator stop lever 54 or 55 causes one or the other of the latter to depress the forward end of the lever 103, by means of laterally projecting lugs 59 or 60 (Fig. 12) formed respectively on the rearwardly extending arms thereof, to disengage the locking detent lever 108 from its accumulator.

Error control mechanism is provided for locking the various denominational orders of the accumulator, actuating mechanism, and the digital key or keys depressed to effectuate an actuation thereof, whenever one or more of such keys is released prior to completion of a full downward stroke thereof. Since the error control mechanism, except as hereinafter indicated, is duplicated in the various denominational or-

ders, only one such order thereof will be herein disclosed in detail.

The error control mechanism prevents mismanipulation of the above-described mechanism due to partial key strokes, retaining a digital key which has been partially depressed in such partially depressed position, substantially equal in depressive extent to the degree of partial actuation imparted thereto, so as to offer a distinct and instantly recognizable visual indication of which key or keys require corrective actuation. Each of the levers 103 is provided to the rear and adjacent its pivot 97 with a lateral extension or shelf 111 (Figs. 9 and 14) which normally rest at its free end on the upper surface of a vertical extension 112 formed on the associated column actuator 26 to limit counter-clockwise movement of the lever 103, as viewed from the left of the machine, by the spring 105. Thus forward movement of the link 95 caused by initial depression of any digit key 25 from its position of Fig. 3 to the partially depressed position of Fig. 4, in the manner hereinbefore described, is accompanied by forward horizontal movement of the lever 103, with the shelf 111 riding on the extension 112 and being held thereon by the spring 105. Such forward movement of the lever 103 is limited by contact of the arm 100 of the swinging link 98 with the cross rod 101.

At this point in the depression of any digital key 25, the projection 53 on its key stem 27 comes into contact with the associated column actuator 26, and further depression of the key, as from the position of the depressed key of Fig. 4 to that of Fig. 5, results in downward swinging of the column actuator to disengage the projection 112 from the shelf 111 and permit the spring 105 to swing the lever 103 about its now stationary pivot 97 to raise its forward end carrying the pin 106 and throw the detent lever 108 into locking engagement with the associated accumulator mechanism. The lever 103 thus assumes its position of Figs. 5 and 10, in which the nose 113 at its rear end, normally extending above a square shaft or bail 114 as seen in Figs. 3 and 9, is now disposed in horizontal alignment with and forwardly of the bail 114. The bail 114 extends laterally across the machine and is supported by arms 115 from a rock bar 116, a spring 117 (Fig. 10), connected between an arm 115 and a punched out lug on a side frame member of the machine, urging pivotal movement of the arms 115 and bail 116 in a counter-clockwise direction, as viewed from the left of the machine. Movement to front or rear of the bail 114, however, is limited by a cross shaft 118 extending through apertures 119 in the arms 115.

Release of a digital key 25 at any partially depressed position, as in Figs. 5 and 10, will result in the usual spring at the bottom of its stem attempting to move it upwardly, and the actuator springs 39 attempting to return the column actuator 26 to normal position. The latter is prevented, however, by the accumulator locking detent lever 108 which is in engagement with the lantern wheel 31. Consequently, the only movement of the parts which is permitted upon release of a partially depressed key is a slight raising of the auxiliary key lock lever 93 by the spring 93 and elbow lever 90 from the position of Figs. 5 and 10 to that of Figs. 6 and 11. This is accompanied, through the agency of the link 95, by a horizontal rearward movement of the lever 103 which is terminated by the nose 113 abutting against and swinging the bail 114 rearwardly

until the forward surfaces of the recesses 119 in the arms 115 contact the cross rod 118. Such movement of the parts is insufficient to disengage the associated tooth 152 on the lever 86 from the recess 151 in the key stem 27 (such parts to be hereinafter described in detail), and since this movement is limited in the manner above described, the partially depressed and released digital key 25 thus is locked in partially depressed position.

Means are provided for retaining the bail 114 in its actuated or rearmost position of Figs. 6 and 11 until corrective actuation of the mismanipulated key or keys have been affected by completely depressing the same. This means comprises in each denominational order a latch lever 121 (Fig. 21) pivotally mounted on a cross shaft 122 at its forward end and terminating at its rear end in a notched portion 123 (Fig. 14). Intermediate its ends the latch lever 121 is provided with a laterally projecting shelf 124 overlying and normally held in engagement with a vertical projection 125 on the lever 103 by a spring 126, in the position shown in Fig. 9. Depression of any digital key 25 results in downward movement of the rear end of the lever 103 to its position of Figs. 5 and 10, as above described, which permits the spring 126 to pull the rear end of the latch lever 121 into contact with the top surface of the bail 114, or into active position. Rearward movement of the bail 114 by the lever 103 when a partially depressed key is released, in the manner described, permits the spring 126 to swing the rear end 123 of the lever 121 down into latching engagement with the bail 114, as shown in Figs. 6 and 11, where it is retained until complete depression of the mismanipulated key raises the rear end of lever 103 to cause projection 125 to strike the shelf 124 and lift the latch lever out of engagement with the bail.

Corrective actuation of the mismanipulated key or keys, comprising complete depression thereof, raises the rear end of the associated lever 103 to its position of Figs. 7 and 12 by virtue of the associated even or odd key stop lever 50 or 51 actuating its actuator stop lever 54 or 55 to cause the lug 59 or 60 thereon to depress the forward end of the lever 103. This also swings the accumulator locking detent 108 out of engagement with the accumulator, in well-known manner, to permit the column actuator 26 to impart additive actuation to the accumulator upon its subsequent upward movement.

Means are provided for retaining the lever 103 with its rear end raised (as shown in Fig. 8) throughout the return additive movement of the column actuator to prevent re-engagement of the lever with the bail 114 and re-engagement of the detent 108 with the accumulator until completion of the upward key stroke. The lever 103 is provided with an upwardly extending arm 127 (Fig. 14) having a lateral projection thereon adapted to cooperate with the upper arm 128 of a latch lever 128, 129 (Fig. 22) pivoted on the cross rod 118; the lower arm 129 normally being engaged by a projection 131 on the column actuator 26, as seen in Fig. 9. A third arm 132 of the latch lever 128, 129 is connected to a spring 133 anchored to a cross shaft 134. Downward movement of the actuator by a digital key releases the lever 128, 129 for active cooperation with the lever 103. At the completion of a key stroke, the resulting downward movement of the forward end of lever 103 from its position of Figs. 6 and 11 to that of Figs. 7 and 12 rocks the

arm 127 forward to permit the arm 128 to be latched behind the lateral projection thereon by the spring 133. Upon return of the column actuator 26 to normal position, the projection 131 thereon disengages the latch lever 128, 129 from the lever 103 to permit the latter to be moved horizontally to the rear by the spring 93. There is a further means for insuring the lever 103 being retained in its position of Fig. 8 during return movement of the column actuator by preventing said lever from tilting during this phase of the operation. This means comprises a latch 135 (Fig. 23) which hooks under the lateral projection on a depending arm 136 on the lever 103 under the influence of a spring 137, when the parts move from their positions of Figs. 6 and 11 to those of Figs. 7 and 12 upon completion of a downward digital key stroke. The latch 135 is pivoted on the cross rod 118, the spring 137 being connected between the upper portion of the latch and a punched out lug on the adjacent machine frame member, and a rearwardly extending arm 138 of latch 135 rests upon cross shaft 122 to limit movement of the latch by the spring 137. These parts fall from their positions of Figs. 7 and 12 to those of Fig. 8 immediately upon release of downward pressure on the digital key after complete depression thereof. As the column actuator 26 arrives at its highest point, the projection 131 disengages the latch 128, 129 from the arm 127 of the lever 103 to permit the latter to be moved horizontally to the rear. During the major portion of such movement, and until such time as the rear nose 113 of the lever 103 is over the bail 114, the lateral projection of the arm 136 rides upon the hook portion of the latch 135, falling below the latter as it slides off of it so as to prevent re-engagement upon subsequent down-strokes of any of the digit keys of the same denominational order.

The stem 27 of each of the digital keys 25 is provided adjacent the projection 38 thereon with a forwardly extending recess 151 (Figs. 12 and 17) adapted to cooperate with a forwardly extending lug or tooth 152 formed on the upper edge of the associated auxiliary key lock lever 86. As will be seen from the drawings, each lever 86 is provided with a plurality of such teeth 152 disposed respectively just to the rear and adjacent each of the associated key stems 27.

Means are provided for moving the auxiliary key lock lever 86 forwardly to engage one of the teeth 152 in the recess 151 of the stem 27 of any digital key 25 upon downward movement of the latter, whereby to lock the depressed key to the column actuator 26 throughout substantially a complete or full key stroke downwardly from and upwardly to the position at which the laterally extending lug 58 on the key stem engages and disengages the column actuator 26. In each denominational order of the machine this means comprises a depending key lock lever actuating lever 153 (shown in perspective in Fig. 15) pivotally mounted at its upper end on a cross rod 154. At its lower end, lever 153 is pivotally connected at 155 to a rearwardly extending link 156. The rear end of the link 156 is provided with a slot 157 (Fig. 3) slidably engaging a pin 158 carried by the associated auxiliary key lock lever 86. A spring 159 connected at its rear end to the pin 158 is attached at its forward end to a laterally extending ear 160 of the link 156. The specific purpose of this yieldable connection between the link 156 and its as-

sociated key lock lever 86 will be described hereinafter.

Adjacent its lower end, the actuating lever 153 is provided with a cam roller 161 and a recess 162, the latter normally engaging a roller 163 mounted on the associated column actuator 26. Referring now particularly to Figs. 3 to 7 and 9 to 12 of the drawings, initial depression of any one of the digital keys 25 from the normal position of Figs. 1 and 9 to the position illustrated in Fig. 4 results in the lug 58 on the stem 27 thereof swinging the auxiliary key lock lever 86 downwardly relative to the column actuator 26 to move the lever 103 forwardly in the manner hereinbefore described. At this point in the downward movement of the key, the lug 58 comes into contact with the upper edge of the column actuator 26. Continued downward movement of the digital key, causing downward swinging movement of the column actuator 26, results in the roller 163 mounted on the latter acting upon the roller 161 to swing the lever 153 forwardly and, through the agency of the link 156 and spring 159, to move the auxiliary key lock lever 86 forwardly from its position of Figs. 3, 4, and 9 into its position of Figs. 5 to 7 and 10 to 12, such movement being permitted by the elongated aperture 84. This forward movement of the lever 86, best seen in Figs. 10 to 12, causes the associated tooth 152 thereon to engage within the recess 151 in the stem of the depressed key. The roller 163 thereafter, during the remainder of the down stroke of the key and the initial portion of its up stroke, cooperates with a rear cam surface 153' (Figs. 10, 15 and 16) of the lever 153 to hold the tooth 152 in the recess 151 of the depressed key stem. Following complete depression of the digital key 25, the active return movement of the column actuator 26 by its springs 39 causes the roller 163 to reenter the cam recess 162 to return the actuating lever 153 and auxiliary key lock lever 86 to their normal inactive positions, such action taking place during the final increment of return movement of the column actuator. The actuated key is thus retained in locking engagement with the lever 86 throughout both downward and upward movement from its initial point of depression, as illustrated in Fig. 4, back to such position in its return to normal.

The previously described operation of the error control mechanism to prevent return movement of the lever 86 upon partial depression and release of a digital key 25 thus functions to retain such partially depressed key in partially depressed position, instead of permitting its return to an initial partially depressed position in the manner of the prior art.

During the time that any digital key 25 is in partially depressed position, means are provided for preventing actuation of any of the other digital keys of the same denominational order. This means comprises a gang or series of key locks 164, Fig. 7, pivotally mounted at 165, respectively, between each adjacent pair of key stems 27. These locks 164 are substantially U-shaped, and have each of their depending arms provided with extensions 166 adapted to engage against shouldered recesses 167 provided in one edge of each of the key stems 27 (Figs. 7 and 17). The locks 164 are so disposed that adjacent extensions 166 thereof are normally substantially in contact with each other in the recesses 167 of the associated key stems 27, there being an aggregate or total spacing longitudinally of the machine between all adjacent extensions 166 of

each ordinal series of key locks 164 equal only to the thickness of one of the key stems 27, so that depression of any key 25 of any particular denominational order will swing the adjacent locks away from the stem of the actuated key, the latter blocking return movement of each of said adjacent locks until said depressed key returns to normal elevated position. Thus, during the time that any key is in a partially depressed position, one of the extensions 166 of each of the 10 locks 164 is engaged in the shouldered recess 157 of each of the other keys in that denominational order to prevent operation thereof.

Means are also provided for locking all of the column actuators against operation whenever any digital key is partially depressed and released, except the column actuator of that denominational order in which a key has been so mismanipulated, to prevent actuation of all of the other keys of the machine until corrective actuation of the mismanipulated key has been made. Pivottally mounted on the cross shaft 134 in each denominational order of the machine is a locking pawl or hook 171. The lower portion of the pawl 171 is normally out of, and adapted to swing forwardly into, engagement with an upstanding hook 172 provided on the column actuator 26, as illustrated in Fig. 9. The upper end of the pawl 171 is provided with a forward extension or arm 173. A bell crank lever 174 is pivottally mounted on the cross shaft 134 in cooperative association with the pawl 171, with one arm thereof engaging against the upper surface of a cross rod 175 carried by the arms 115, and the lower arm thereof connected by a spring 176 to the depending portion of the pawl 171. The spring 176 thus functions to retain the forwardly extending arm 173 of the pawl 171 against the under surface of the cross rod 175.

Upon clockwise movement of the bail 114 and arms 115 as hereinbefore described, from the position of Figs. 9 and 10 to the position of Fig. 11, due to partial depression and release of a digital key, the cross rod 175 is moved upwardly to swing all of the pawls 171 in a counter-clockwise direction. Such movement of the pawls 171 moves the depending arms thereof forwardly to cause their engagement with the associated hooks 172 to prevent downward movement of the column actuators 26 in all denominational orders of the machine other than that of the mismanipulated key. At this time, accumulator locking detent lever 108 in that denominational order in which a key has been mismanipulated is functioning as above described to prevent upward or return movement of its associated column actuator. Upon complete depression of the mismanipulated key, return of the bail 114 and arms 115 to normal position in the manner hereinbefore described will be accompanied by downward movement of the cross rod 175 to return all of the pawls 171 to normal or inoperative position.

Means are provided, particularly useful during the performance of addition or subtraction, to prevent such return of the locking pawls 171 to normal position upon corrective actuation of a mismanipulated key so as to effect complete locking up of the entire machine, including the mechanism of that denominational order in which an error in key depression has been made and corrected. This means comprises mechanism mounted to the left of the highest denominational order of the machine for selective active association with the rockable cross rod or bail 114 carried by the arms 115, as best illustrated

in Figs. 18 and 19. Pivottally mounted on a shaft 181 at the left-hand side of the machine is a latch lever 182, the rear end of which normally rests upon the upper surface of the bail 114 (as shown in Fig. 18) and is provided with a retaining notch 183. A spring 184 connected at its upper end to a cross rod 185 is connected at its lower end to the latch lever 182 forwardly of its pivot 181 to urge and yieldably retain the latch lever in engagement with the bail 114. When the error control mechanism is rendered operative in the manner hereinbefore described, causing the bail 114 to be swung rearwardly from its position of Fig. 18 to its position of Fig. 19, the latch lever 182 is swung into the operative position of the Fig. 19 by the spring 184. Consequently, subsequent corrective actuation of the key or keys which have been mismanipulated, while causing the remainder of the error control mechanism to be returned to normal position as previously described, nevertheless results in complete locking of the machine by virtue of the action of the latch lever 182 retaining the bail 114, and consequently the locking pawls 171, in active position. The spring 176 of the locking bail assembly 171 in that denominational order in which corrective actuation has been applied to a mismanipulated digital key permits the hook 172 on the column actuator 26 of that order to swing the pawl 171 rearwardly as it rises to normal position and then functions to return said bail forwardly into active locking engagement with that hook 172.

Control mechanism is provided which is manually operable to release for actuation the entire keyboard thus locked. This mechanism comprises an error release key 186 centrally located at the forward end of the machine (Figs. 1 and 2) which is connected to the forward end of a laterally and rearwardly extending lever 187 in the form of a rod pivottally mounted in a suitable bearing at 188 (Figs. 2 and 18) and extending downwardly and rearwardly from such pivot point. The rearward terminal end of the rod 187 abuts against a suitable pad provided on the depending end of a bell crank lever 189 which is pivoted intermediate its ends on the cross shaft 135. Spring 190 holds the depending end of the lever 189 in yielding engagement with the rear end of the rod 187. Following movement of the latch lever 182 into its active position of Fig. 19 by the spring 184, release thereof may be effected by downward movement of the error release key 186, resulting in raising of the rear end of the rod 187 to swing the lever 189 in a clockwise direction, as viewed from the left side of the machine, to lift the latch lever 182 out of engagement with the bail 114 to permit the arms 115 and the locking bails 171 to be returned by the spring 117 to normal or inoperative position.

Means are also provided for accomplishing this same result of releasing for actuation the entire keyboard following locking thereof due to mismanipulation of a digital key and subsequent corrective actuation thereof whenever the canceling mechanism is operated to zeroize the accumulator. As is well known, and specifically illustrated in Patent No. 1,357,747, zeroizing of the accumulator in this type of machine is accomplished by detraining the gears 32 from the gearing of the lantern wheel shaft 30 to release the carrying springs 41 to permit them to turn the several registering wheels rearwardly from their various positions to normal or zero position. To effectuate such action, a zeroizing handle or canceling crank 71 is provided (Fig. 18) which is

pivoted adjacent its lower end and swung forwardly, or clockwise as viewed in Fig. 18, for zeroizing, and is connected by a link 73 to a depending lever 74 that is pivoted at its upper end by being rigidly mounted on a rock shaft 75 rotatably mounted on the frame of the machine. The lower end of the lever 74 is pivotally connected by means of a link 76 with an arm 77 rotatably mounted with respect to a transverse shaft 78 that is journaled on the frame of the machine. The arm 77 is provided with an engaging face 79 adapted to contact with a second arm 80 fixed on the shaft 78. Forward swinging movement of the canceling crank 71 (clockwise in Fig. 18) thus imparts a short rocking movement to the shaft 78 to swing the frame carrying the gears 32 forwardly to detrain the same from the gearing of the lantern wheel 39 and also to impart a slight counter-clockwise rotation to the rock shaft 75, all as described in said Patent No. 1,357,747.

The rock shaft 75 has rearwardly extending arms 81 secured thereto in each denominational order of the machine for cooperation during zeroizing with the rear ends of the locking detent levers 108 (Fig. 2) as described in the prior listed patents and particularly No. 1,357,747, and one such arm adjacent the left end thereof which extends rearwardly over the forward end of the bell crank lever 189 (Fig. 18). Zeroizing of the accumulator thus results in clockwise movement of the bell crank lever 189, as viewed in Figs. 18 and 19, to release the latch lever 182 from engagement with the bail 114 in the manner above described.

Error correction control means, particularly useful during the performance of multiplication and division, is selectively operable to render ineffective the above described means for locking partially depressed keys following corrective actuation thereof. For that purpose an error correction control key 196, as shown best in Figs. 1, 13, and 20, is mounted at the left side of the machine. Intermediate its ends, the stem of the error correction control key 196 is connected by a pin and slot connection 196' to the rear end of a forwardly extending link 197. The forward end of that link 197 is provided with a slot 197' slidably engaging a reduced portion of the rock shaft 75 and is connected by a spring 198 to an intermediate portion of the stem of the error correction control key 196. The link 197 is stamped or otherwise provided at its forward end with a lug 198' extending laterally to the right of the link and is engageable by a pin or other projection 75', depending from the rock shaft 75, during zeroizing operations of the shaft 75 while the key 196 is in its active or set position of Fig. 20, to release the key 196 for return to its elevated position of Fig. 18.

Adjacent its upper end, the stem of the error correction control key 196 is provided with a rearwardly extending shoulder 199 adapted to cooperate with a stationary cross shaft 200, and to be held in yieldable engagement therewith when the key 196 is depressed and moved rearwardly to its active or set position of Fig. 20 by a spring 201 connected between a cross shaft 202 and the lower end of the stem of the key 196. Adjacent the lower end of the stem of the key 196 is pivotally connected the forward end of a lever 203 rotatably mounted at its rear end on a cross shaft 204. A third arm of the lever 203 is provided with a notched portion 205 for cooperation with the cross shaft 202 to limit vertical movements of

the lever 203 and the error correction control key 196. The lever 203 is also provided with a laterally projecting portion 206 overlying the forward end of the latch lever 182.

When moved from its elevated position of Fig. 18 to its active or set position of Fig. 20, the error correction control key 196 may be moved slightly rearward where it will be retained by the spring 201 holding the shoulder 199 in frictional contact with the shaft 200. During the rearward movement of the key 196 as just described, the spring 198 moves the link 197 rearwardly to bring the lug 198' into, and yieldably hold it in, its position for engagement by the pin 75' during any zeroizing operations of the shaft 75 which may occur while the key 196 is in its active or set position. Movement of the error correction control key 196 to this lowered or active position results in releasing the latch lever 182, if the latter is in its active position of Fig. 19, and retains the same in its inoperative position of Fig. 20. With the error correction control key 196 in this active position, complete depression of all digital keys 25 which have been locked in partially depressed position causes immediate automatic unlocking of the entire keyboard upon complete corrective depression of the last of such mismanipulated digital keys. The above described sliding connection of the link 197 with the rock shaft 75 results in automatic release of the error correction control key 196 from its active position of Fig. 20 and return thereof to its normal or inoperative position of Fig. 18 by the spring 201 whenever the cancelling crank 71 is operated to rotate shaft 75 in the manner previously described to cause zeroizing of the accumulator.

During the zeroizing operation the shaft 75 is rotated in a counter-clockwise direction as seen in Fig. 20 which causes the pin 75' to engage the lug 198' and thereby to operate the link 197. During the operation of the link 197 by the pin 75', the link 197 depresses the error correction control key 196 very slightly below its position of Fig. 20, which is sufficient to relieve the upward pressure of shoulder 199 against rod 200 as maintained by spring 201 when key 196 is in its active position of Fig. 20, and the pin 75' moves the link 197 forwardly sufficiently to cause spring 198 to swing the key 196 in a clockwise direction to clear the shoulder 199 from the rod 200. The spring 201 thereafter elevates the key 196 to its initial position of Fig. 18, spring 198 resiliently maintaining shoulder 199 out of the path of rod 200 during return movement of zeroizing crank 71 and shaft 75. If it is desired to retain the key 196 in its set or active position of Fig. 20 during and after a zeroizing operation, the operator manually holds the key in its set or active position, and the spring 198 cooperates with the slideable connections at the opposite ends of the link 197 to permit the necessary relative movement between the link and the key 196 and shaft 75 and thereafter to return the link to the position of Fig. 20 where, unless the key 196 is so held, it may be automatically returned to its initial or elevated position during the next zeroizing operation, as already described.

The yieldable connection previously described between the column actuator 26 and the auxiliary key lock lever 85, comprising the spring 159, is provided for the purpose of preventing injury to the actuating mechanism and associated parts if an inexperienced operator attempts to forcibly return a partially depressed digital key 25 to a normal position by raising the same without

completing a full depression thereof. With this arrangement, an upward forcing of a key stem 27 of a key which has been partially depressed will merely cause forced disengagement thereof from the associated tooth 152 on the key lock lever 36 against the action of the spring 159.

From the foregoing description of the instant embodiment of the present invention, the necessity of providing error control mechanism operable differently during different types of calculation to obviate and correct mismanipulation due to partial depression of ordinal keys in the manner best suited to the particular method of machine calculation being employed will now be understood more easily. As has been noted, in the performance of addition, for example, in this type of machine it is preferred to employ the "touch" method to attain the greatest degree of speed and accuracy, in which method only the lower half of the keyboard is used. The keys are individually operated, one at a time, and where the digital value in any particular order exceeds five, the operator either depresses a plurality of keys in that order, the added values of which total the number exceeding five, or he depresses one key representing a whole fraction of the number exceeding five, a proper number of times to total that number exceeding five. Hence, the operator in addition is frequently called upon to resort mentally to simple factoring and to keep in mind a definite number of strokes necessary in one or more orders to add into each such order a single ordinal number. Consequently, in rapid operation where, for example, eight is to be added in a particular order, the operator might hit the "4" key and partially depress it, counting that as one stroke. Upon learning of his error by finding the keyboard locked, he would again strike the "4" key completely depressing it, and methodically count that as a second stroke. Obviously, if that should happen and the keyboard were not thereafter locked, the operator would proceed with the problem in addition on the assumption that the two operations of the "4" key had resulted in the addition of eight, whereas only four would have been added. The fact that in addition the entire keyboard is locked upon completing the depression of a partially depressed key enables the operator to find his error and to be sure that he has properly corrected it before proceeding with the problem.

In multiple operation of the machine, on the other hand, such as multiplication, it is important that the keyboard be automatically unlocked following corrective actuation of a mismanipulated key. In multiplication the fingers are arranged to strike a plurality of keys in different denominational orders simultaneously and repeatedly, and the finger arrangement (representing the multiplicand) is maintained throughout the performance of the multiplication problem, the hand or hands being shifted from time to time one denominational order to the left and repeatedly operated in accordance with the digital and denominational value of the different figures of the multiplier. Thus in the event of partial depression of any one key, the operator, upon learning of such mismanipulation due to the locking of the keyboard, can, without changing his finger arrangement, merely completely depress the mismanipulated key to correct the error and unlock the keyboard. That, of course, can be done by resting the tips of the arranged fingers on or just above the proper keys and, while holding them in that position, utilize the

finger aligned with the partially depressed key individually to complete the depression of that mismanipulated key. In the event that more than one key was mismanipulated, the same corrective action is taken, each partially depressed key being fully depressed without necessitating re-alignment of the fingers, and upon corrective actuation of all mismanipulated keys the keyboard is automatically unlocked to permit continuation of the problem without necessitating re-alignment of the fingers. If, on the other hand a separate button or key had to be operated for thereafter unlocking the keyboard, as in addition, it would be necessary for the operator to change his finger arrangement, and after operation of the separate error correction key, re-arrange his fingers to continue the problem.

In conjunction with the above-described operation of the instant mechanism, either in individual or in simultaneous and repetitive depression of the ordinal keys, the key lock lever 36, its actuating lever 153, and associated parts function to releasably latch any depressed key to its column actuator throughout the active phase of each complete operation of the key, so that upon partial depression and release of any ordinal key, the resulting operation of the previously described error locking mechanism will result in the partially depressed key or keys being retained in such partially depressed position to give a distinct visual indication of which keys require corrective actuation.

The above described novel error preventing mechanism is so arranged that it will necessitate the desired sequence of operations for correcting mismanipulation of the machine. More specifically, when the error correction control key 196 has been depressed prior to operation of the digital keys 25 to condition the machine for multiplication and division, the machine will again be properly conditioned for normal operation following partial depression of one or more of the digital keys 25 only if all of such partially depressed keys have been correctively actuated by fully depressing the same. This is true because of the fact that any one of such partially depressed keys, so long as it remains in partially depressed position, will prevent return of the bail 114 to normal position following complete depression of all of the other digital keys which may have been partially depressed at the same time. Such is the case because return of the error control mechanism in a manner herein described upon complete depression of one partially depressed key will not effectuate release of the latch 121 from the bail 114 in any other denominational order in which a digital key has been partially depressed. Likewise, when the error correction control key 196 is in normal or raised position so that the machine is conditioned for additive or subtractive operation, all of those digital keys 25 which have been partially depressed must be correctively actuated and the error release key 186 depressed (or the canceling crank 71 operated) before the machine will again be properly conditioned for normal operation. Partial depression of two keys simultaneously with the machine so conditioned for addition and subtraction and subsequent corrective actuation of only one of the said partially depressed digital keys followed by actuation of the error release key 186 will not function to release the key board for normal operation. Expressed differently, operation of the error release key 186 must be performed in its proper sequence in order to recon-

dition the machine following mismanipulation for normal operation. After one or more of the digital keys 25 have been mismanipulated by being only partially depressed, actuation of the error release key 186 is ineffective, unless all of such mismanipulated keys have been correctively actuated. This is due to the fact that depression of the error release key 186 with the machine in the locked condition resulting from partial depression of a digital key 25 will only raise the rear end of the latch lever 182 from engagement with the bail 114 and the bail will not be released from its active, latched position but will be retained in such position by the latch 121 in that denominational order in which a digital key 25 remains in partially depressed position. Consequently, normal operation of the machine may be resumed following mismanipulation and corrective actuation of any partially depressed keys without zeroizing the accumulator and starting the particular calculation over again, since the above described mechanism insures the correct degree of actuation being imparted to the accumulator. If the above described sequence of operations in correcting errors of mismanipulation were not enforced in the manner described, and actuation of the error release key 186 was permitted to return the parts to normal position without first requiring corrective actuation of all partially depressed keys, the accumulator would be actuated, in that denominational order in which a mismanipulated key had been permitted to remain in partially depressed position without corrective actuation, in lesser degree than that intended and necessary to accurate operation.

It is thought that the invention and its attendant advantages will be understood from the foregoing description, and it will be apparent that various changes may be made in the form, construction and arrangement of the parts without departing from the spirit and scope of the invention or sacrificing all of its material advantages, the form hereinbefore described and illustrated in the drawings being merely a preferred embodiment.

I claim:

1. In a multiple order calculating machine having accumulator mechanism, and denominational orders of digital keys for controlling actuation of said accumulator mechanism; means operable upon partial depression of any of said keys for locking such keys in partially depressed position, locking means automatically actuated in response to operation of said first means for preventing depression of any key in any denominational order other than those of said partially depressed keys, means for automatically releasing both of said locking means immediately upon complete depression of all of such partially depressed keys, and settable means selectively operable to render the last said means ineffective and to lock all of the keys against depression upon corrective actuation of said partially depressed keys.

2. In a multiple order calculating machine having accumulator mechanism, and denominational orders of digital keys for controlling actuation of said accumulator mechanism; means operable upon partial depression of any of said keys for locking such keys in partially depressed position and for preventing operation of any key in any denominational order other than those of such partially depressed keys, means for preventing operation of the keys in those denominational orders in which a key has been partially depressed upon corrective actuation of such partially depressed

key, and selectively operable means for rendering the last said means ineffective and causing automatic release of the operation preventing means upon corrective actuation of all partially depressed keys.

3. In a multiple order key-driven calculating machine having accumulator mechanism, denominational orders of actuating mechanism for said accumulator mechanism, and digital keys individually depressible for operating said actuating mechanism in addition and subtraction and repetitively and simultaneously depressible for operating said actuating mechanism in multiplication and division; locking means, including mechanism operable upon partial depression of any of said keys for locking such keys in partially depressed position, and mechanism automatically operable in response to operation of said last mechanism for preventing depression of any key in any denominational order other than those of said partially depressed keys; means settable for additive and subtractive operation of the machine and responsive to operation of the locking means for preventing operation of any of said keys upon corrective actuation of all such partially depressed keys.

4. In a multiple order calculating machine having denominational orders of digital keys one of which in a number of orders is individually operable and any one of which in an order is simultaneously and repetitively operable with one in each of a number of different orders to control the actuation of said machine in various forms of calculation, and means for preventing the operation of more than one of said digital keys at a time in any denominational order; manually operable means selectively settable when the machine is to be used for different forms of calculation comprising individual operation of the digital keys or simultaneous and repetitive operation of the digital keys, locking means, comprising mechanism operable upon partial operation of any of said digital keys for holding each partially operated key in its partially operated position, and mechanism operable in response to operation of said last mechanism for releasably locking all of the other digital keys against further operation in all denominational orders other than those containing partially operated keys; and manually operable release means for said key locking means, controlled by said manually operable settable means, for releasing the locked keys after completing the operation of the partially operated keys.

5. In a multiple order calculating machine, denominational orders of digital keys operable to control the actuation of said machine, locking means, including mechanism operable upon the partial operation of a number of said digital keys for holding each partially operated key in partially operated position, mechanism operable in response to operation of said last mechanism for releasably locking all of the other digital keys in all denominational orders other than those of said partially operated keys against further operation, and manually controlled means for maintaining said other digital keys releasably locked against further operation and for causing the locking of each partially operated key upon completion of its operation; and manually operable means

adapted to render said manually controlled means ineffective and to release said other digital keys for further operation upon completion of the operation of all of the partially operated keys.

6. In a multiple order calculating machine having accumulator mechanism, and denominational orders of digital keys for controlling actuation of said accumulator mechanism; a first locking means operable upon partial depression of any of said keys for locking such keys in such partially depressed position, a second locking means operable by said first locking means for preventing depression of any key in any denominational order other than those of said partially depressed keys, and manually operable means effective only following corrective actuation of all of said partially depressed keys for releasing said second locking means to permit normal operation of the machine.

7. In a multiple order calculating machine, denominational orders of digital keys for controlling actuation of the machine, locking means including mechanism operable upon partial depression of any of said keys for locking said keys in partially depressed position and mechanism operable in response to said first mechanism for preventing operation of all of the others of said keys, comprising a bail cooperatively associated with all of the denominational orders of the machine and a latch member in each denominational order of the machine rendered effective to latch said bail in operative position upon partial depression of any digital key in the denominational order associated therewith; latching means automatically operable upon movement of said bail resulting from partial depression of any of said keys to retain the bail in operative position, means operable upon complete depression of each said partially depressed keys to render ineffective the said latch member associated therewith, and manual means operable to release said latching means and free said bail for return to inoperative position for freeing for operation all of said keys only upon release of said latch members associated with all of said partially depressed keys.

8. In a multiple order calculating machine having accumulator mechanism, denominational orders of actuating mechanism for said accumulator mechanism, and a plurality of digital keys for controlling the operation of each of said denominational orders of actuating mechanism; locking means, comprising mechanism operable upon partial actuation of any of said digital keys for locking said keys in such partially actuated position, and mechanism operated by said first mechanism for preventing operation of said actuating mechanism in all denominational orders other than those of said partially actuated keys, including means operable to lock the actuating mechanism in those denominational orders in which said keys have been partially actuated following complete actuation thereof; and means for locking the actuating mechanism locking means, effectively operable manually to release the same to condition it for normal operation only following complete actuation of all of said partially actuated keys.

9. In a calculating machine, depressible keys for controlling actuation of the machine, latch means operable upon partial depression of any of said keys for latching and retaining said keys in partially depressed position, and yieldable means for yieldably holding the latch means in key retaining position, said yieldable means being yieldable when said partially depressed keys are lifted

to permit forced lifting of said partially depressed keys to normal position without resulting damage to the machine.

10. In a multiple order calculating machine, denominational orders of digital keys for controlling actuation of the machine, means operable upon partial actuation of any of said keys for locking such keys in partially actuated position, means operable in response to the operation of said last means for preventing operation of any key in any denominational order other than those of such partially actuated keys, means for automatically releasing both of said locking means upon complete actuation of all of such partially actuated keys, and means for rendering the last said means ineffective and selectively operable upon complete actuation of all of said partially actuated keys to enable further operation of any of said keys.

11. In a calculating machine, accumulator mechanism, actuating mechanism having an actuator element for actuating said accumulator mechanism, a plurality of keys for operating the actuator element of said actuating mechanism, normally inoperative key lock mechanism operable automatically upon depression of any of said keys to releasably latch said key to said accumulator actuator element for substantially the full downward and upward movement of said key, and means automatically operable upon release of said key at any point during its depression short of a full down stroke to lock said actuator element in partially operated position against return to normal position to retain such key in partially operated position, said key lock mechanism preventing damage to the machine from forced raising of said mis-manipulated key to normal position by permitting disengagement of said key from its actuator element.

12. In a calculating machine having a plurality of keys in each of a plurality of denominational orders, an accumulator having a plurality of denominational orders, and actuator mechanism for actuating said accumulator having an actuator element in each denominational order operable by the keys therein; normally inoperative denominational key lock mechanism operable automatically upon depression of any key in any denominational order to releasably latch said key to its associated accumulator actuator element for substantially the full downward and upward movement thereof, and means automatically operable upon release of said key at any point during its depression short of a full down stroke to lock said actuator element in such partially depressed position against return to normal position to maintain said mis-manipulated key in such partially depressed position, said key lock mechanism preventing damage to the machine from forced raising of said mis-manipulated key to normal position by permitting disengagement of said key from its actuator element.

13. In a multiple order calculating machine having accumulator mechanism and denominational orders of digital keys for controlling actuation of said accumulator mechanism; locking means operable upon partial depression and release of any of said keys for holding such mis-manipulated keys in such partially depressed position and preventing depression of any of the others of said keys, including intraordinal key locks in each order operable upon depression of any one key therein to prevent depression of any other key in the same order, a normally inoperative bail disposed transversely of the machine

across all denominational orders thereof, means in each denominational order operable in response to the mis-manipulation of any associated key to move said bail to operative position to prevent depression of any key in any other denominational orders of the machine, and a latch in each denominational order automatically operable in response to operation of said last recited means to retain said bail in operative position; and means for automatically releasing said locking means only upon complete depression of all of such mis-manipulated keys including means in each denominational order operable upon complete depression of any key in said order to move said associated latch out of engagement with said bail.

14. In a multiple order calculating machine having accumulator mechanism and denominational orders of digital keys for controlling actuation of said accumulator mechanism; locking means operable upon partial depression and release of any of said keys for holding such mis-manipulated keys in such partially depressed position and preventing depression of any of the others of said keys, including intraordinal key locks in each order operable upon depression of any one key therein to prevent depression of any other key in the same order, a normally inoperative bail disposed transversely of the machine across all denominational orders thereof, means in each denominational order operable in response to the mis-manipulation of any associated key to move said bail to operative position to prevent depression of any key in any other denominational orders of the machine, and a latch in each denominational order automatically operable in response to operation of said last recited means

to retain said bail in operative position; means for automatically releasing said locking means only upon complete depression of all of such mis-manipulated keys, including means in each denominational order operable upon complete depression of any key in said order to move said associated latch out of engagement with said bail; and manually releasable means operable to render ineffective said automatically operable releasing means by retaining said bail in operative position to lock all of the keys against depression following complete depression of all mis-manipulated keys, and selectively settable to inoperative position to enable effective operation of said automatically operable releasing means.

FREDERICK A. NIEMANN.
